UNITED STATES PATENT OFFICE

2,064,656

ELECTRORESPONSIVE DEVICE

Robert W. Goff, Schenectady, N. Y., assignor to
General Electric Company, a corporation of
New York

Application February 28, 1935, Serial No. 8,652

8 Claims. (CL 200—97)

My invention relates to electroresponsive devices, more particularly to electroresponsive devices of the type which are operable manually to open and close quickly a circuit and which are automatically operable with a time delay to open the circuit, and has for an object the provision of a simple, reliable and inexpensive device of this character.

Electroresponsive devices embodying my invention are particularly applicable to undervoltage protective systems for electrical circuits wherein deenergization of the electrical translating devices, for example, electric motors, in the circuit is accomplished upon a predetermined dip in the line voltage, the electroresponsive device being effective to reenergize the circuit if the voltage dip exists for a predetermined time only and to prevent automatic reenergization of the circuit if the dip in voltage exists beyond that time. It has heretofore been proposed to combine an electroresponsive device of this type with manually operable means for interrupting the circuit independently of the voltage conditions. Much is yet to be desired, however, in a combined manually operable and automatic undervoltage protective station so arranged that either instantaneous or timed operation can be had at any time without possibility of injury to the operating mechanism. Accordingly, it is a further object of my invention to provide an electroresponsive device adapted to open a circuit with a time delay in response to conditions in the circuit to be controlled, the electroresponsive device being provided with manually operable means for interrupting the circuit at will without injury to the automatically operable mechanism.

In carrying out my invention in one form, I provide an electroresponsive device energizable in accordance with the voltage of a circuit to be controlled and a timing mechanism for delaying the opening of a pair of circuit controlling contacts upon the occurrence of a dip in the line voltage, the timing mechanism being driven by a segmental gear mounted on a floating pivot and rotatable about the pivot in accordance with the energization of the electroresponsive device. Instantaneous operation of the contacts is obtained by moving the floating pivot in a direction to disengage the segmental gear from the driving element of the timing device, and means are also provided for insuring that the segmental gear and the driving element of the timing device return to meshable relation after an instantaneous operation of the contacts.

As a further aspect of my invention, I provide a control device manually operable by means of a control lever or shipper rod for closing a pair of contacts to energize the electroresponsive device and maintain a holding circuit therefor, the control device being arranged automatically to free the contacts for automatic operation to the open circuit position by the electroresponsive device at any time.

For a more complete understanding of my invention, reference should now be had to the drawings in which Fig. 1 is a diagrammatic perspective view of an electroresponsive device embodying my invention applied to an undervoltage protective system; Fig. 2 is an enlarged view, partly in section, of a portion of the mechanism shown in Fig. 1; Fig. 3 is a sectional elevation of a portion of the timing mechanism shown in Fig. 1; Fig. 4 is a sectional elevation of the mechanism shown in Fig. 3; Fig. 5 is a sectional view of a control device for providing shipper rod operation of the electroresponsive device shown in Fig. 1; Fig. 6 is an elevational view of the device shown in Fig. 5 with certain parts broken away to show the construction more clearly; and Fig. 7 is a sectional view taken along the line 7—7 of Fig. 6.

Referring now to Figs. 1 to 4 inclusive, I have shown my invention in one form as applied to a combined automatic undervoltage and manually operable control station comprising an electroresponsive device 10 and a pair of manually operable push buttons 11 and 12 for controlling the energizing winding 13 of a contactor 14 which is connected in a load circuit represented by the conductors 15 and 16 and which is provided with a pair of interlock contacts 17. The electroresponsive device 10 comprises an energizing winding 18 and a movable magnetic element 19 normally biased by gravity to its unattracted position and connected by means of a link 20 to an operating member or segmental gear 21 pivoted on a movable pivot pin 22. When the segmental gear 21 is in the position shown in the drawings, an end portion 23 thereof engages a switch member 24 which is mounted on a pivot pin 25 and provided with a bridging member 26 in cooperating relation with a pair of contacts 27, the segmental gear 21 being effective in this position to maintain the bridging member 26 in its open circuit position against the biasing force exerted on the switch member 24 by a spring 28.

In order to provide for time delay operation of the magnetic element 19 and the segmental

gear 21 from the attracted position of the magnetic element 19 to the position shown in the drawings, I provide time delay means including a toothed element or driving pinion 29 arranged 5 to mesh with the teeth 30 formed on the segmental gear. Although any suitable time delay mechanism may be provided which will permit substantially instantaneous operation of the pinion 29 in one direction and will provide time 10 delay operation of the pinion in another direction, I have shown for purposes of illustration, a timing device of the type described and claimed in Patent No. 1,967,880, issued July 24, 1934, to William J. Fleming and me. This timing device comprises an oscillating weight 31 15 rotatably mounted on a shaft 32 to which the pinion 29 is secured, which weight is arranged to be driven by an escapement gear 33 connected to a shaft 34 which operates a driving member 20 35 adjustably secured to a pin 36, one end of which nests within a slot 37 in the oscillating weight 31. The shaft 32 supports a second escapement gear 38 for driving the escapement gear 33.

25 In order to permit substantially instantaneous operation of the segmental gear 21 when the winding 18 is energized, the escapement gear 38 is provided with a one-way clutch which is effective to establish a driving connection between 30 the shaft 32 and the gear 38 only when the magnetic element 19 moves to its unattracted position upon deenergization of the winding 18. Referring to Figs. 3 and 4, it will be seen that the escapement gear 38 is cylindrical in form, the 35 inner surface of the gear being provided with a plurality of serrations or very fine gear teeth 39. Supported by the shaft 32 is a spider 40 on which are pivotally supported a plurality of clutch members 41 provided with sharpened ends 40 for engaging the teeth 39 when the shaft is rotated in a counterclockwise direction as viewed in Fig. 3, the clutch members 41 being ineffective 45 to establish a driving connection with the escapement gear 38 when the shaft 32 is rotated in the opposite direction.

50 In order to provide for substantially instantaneous operation of the switch member 24 to the open circuit position, the stop button 11 is mounted on a pair of movable arms 42, one of 55 which is provided with a pin 43 arranged to engage a projection 44 on the switch member 24. The movable arms 42 are pivoted on a fixed pivot pin 45 and support the movable pin 22 on which the segmental gear 21 is pivoted, and a spring 46, one end of which engages the pin 45 and the other end of which is secured to the segmental gear 21, is provided for biasing the gear 21 and the movable arms 42 to the position shown in Fig. 1 of the drawings. The start 60 button 12 is normally biased by a spring (not shown) to the open circuit position shown in the drawings and is provided with a pair of fixed contacts 47.

65 Having in mind the construction and arrangement of the principal elements thereof, it is believed that a complete understanding of my invention may now be had from a description of the operation. When the start button 12 is depressed to close the contacts 47, an energizing 70 circuit for the winding 13 of the contactor 14 is completed which may be traced from the supply line 48 through the contacts 47, the conductor 49, the conductor 50, the winding 13 and the conductor 51 to the supply line 52. Simultaneously 75 with the closing of the contactor 14, the inter-

lock contacts 17 are closed to establish an energizing circuit for the electroresponsive device 10, which circuit may be traced from the supply line 48 through the contacts 47, the conductors 49, 50 and 53, the interlock contacts 17, the conductor 54, the energizing winding 18 and the conductor 55 to the supply line 52. Upon the energization of the winding 18, the magnetic element 19 will be moved to its attracted position and the segmental gear 21 will be rotated about 10 its pivot to permit the switch member 24 to move in accordance with the bias exerted by the spring 28 to establish a holding circuit for the contactor 14 and the electroresponsive device 10. The holding circuit for the winding 13 may be 15 traced from the supply line 48 through the conductor 56, the contacts 27 and the bridging member 26, the conductor 50, the winding 13 and the conductor 51 to the supply line 52, and the holding circuit for the electroresponsive device 10 20 may be traced from the supply line 48 through the conductor 56, the contacts 27 and the bridging member 26, the conductors 50 and 53, the contacts 17, the conductor 54, the winding 18 and the conductor 55 to the supply line 52. Since 25 these holding circuits are automatically completed as soon as the contactor 14 is closed it will be seen that it is only necessary momentarily to depress the start button 12.

30 It will be apparent that the contactor 14 and the electroresponsive device 10 will remain in their respective energized positions so long as normal voltage is maintained across the supply lines 48 and 52. Upon the occurrence of a dip 35 in voltage, however, the windings 13 and 18 will be deenergized, the contactor 14 immediately moving to the position shown in the drawings to deenergize the load circuit and the magnetic element 19 of the device 10 being released for movement to the position shown in the drawings. 40 Movement of the magnetic element 19 and the segmental gear 21 to this position, however, is retarded by the time delay mechanism so that the switch member 24 is not immediately operated to its open circuit position. Accordingly, 45 if normal voltage should return to the supply lines 48 and 52 before the device 10 has completely timed out, the winding 13 of the contactor 14 will be reenergized through the previously traced holding circuit and the interlock contacts 17 will close to reestablish the previously traced energizing circuit for the winding 18.

50 If it is desired to open the holding circuit instantaneously to deenergize the winding 13, it is only necessary to depress the stop button so 55 as to move the arms 42 about the pivot pin 45. When the arms 42 are so moved, the pin 43 will engage the projection 44 and thereby operate the switch member 24 to open the circuit through the contacts 27. The windings 13 and 18 are thereby deenergized and since the movable pivot 22 is at the same time operated to move the segment gear 21 out of engagement with the pinion 29, the segmental gear 21 and the magnetic element 19 will immediately move to the 60 normal position shown in the drawings so as to retain the switch member 24 in its open circuit position when the stop button 11 is released.

65 Since the stop push button 11 may be operated at any time, it will be apparent that the pinion 29 may come to rest in a position such that when the stop button 11 is released the pinion 29 will not be in meshable relation with the 70 75

teeth 30 on the segmental gear 21 and, accordingly, I provide means for automatically positioning the pinion 29 in meshable relation with the segmental gear 21 after each instantaneous 5 operation of the switch member 24 by means of the push button 11.

Referring to Fig. 2, it will be seen that the segmental gear 21 is provided with a toothless portion 57, the teeth 30 extending from the end 23 of the segmental gear to the portion 57. The curvature of the portion 57 is such that when the pinion 29 is in the position shown in Fig. 1 with a pair of adjacent teeth engaging the portion 57, the pinion 29 will be in meshable 10 relation with the teeth 30. It will be remembered that the spring 46 surrounds the pivot pin 22 with one end of the spring engaging the fixed pivot pin 45 and the other end of the spring secured to the segmental gear 21 so that 15 not only is the segmental gear urged in a counterclockwise direction about the pivot 22, but also the pivot 22 is urged in a clockwise direction about the pivot 45 to move the pivoted end of the segmental gear 21 toward the pinion 29. It 20 will be apparent, therefore, that if the pinion 29 comes to rest with one tooth thereof engaging the portion 57 at an angle, the frictional force exerted on the pinion 29 by the segmental gear 21 will quickly rotate the pinion 29 to the position 25 shown in the drawings. If the pinion 29 comes to rest in a position such that one tooth is perpendicular to the surface 57, an unstable support is formed for the segmental gear 21 and the slightest movement of the segmental gear 21 30 will cause the pinion 29 to be rotated, and the segmental gear 21 will thereupon be quickly moved to the position shown in Fig. 2.

In certain applications of my invention, for example, in the control of manufacturing machinery, it is desirable to operate the control device from a distance. In many cases this may 40 advantageously be done mechanically by means of a control lever or shipper rod, and in Figs. 5, 6 and 7 of the drawings I have shown a device adapted to be operated by a shipper rod to 45 control the switch member 24.

In this embodiment of my invention, the push buttons 11 and 12 and the contacts 47 may be omitted, the shipper rod attachment being arranged to operate directly the switch member 24. For convenience, the switch member 24 is 50 extended a short distance below the contacts 27, this extension being identified by the reference numeral 58.

Secured to a base 59 of the electro-responsive device 10 is a pin 60 on which is slidably mounted a reciprocal member 61 to which is pivotally connected a link 62 arranged to be operated through a lost motion connection 63 by any suitable operating lever such as a shipper rod, one end of which is indicated by the reference numeral 64. The reciprocal member 61 is provided with two longitudinally spaced depressions 65 and 66, the adjacent walls of which meet in a crest 67, and a control member 68 preferably formed of insulating material is slidably mounted on the reciprocal member 61 and normally held in one or the other of two positions by driving means comprising a plurality of steel balls 69 60 disposed in guides 70 in the control member 68. The control member 68 is also provided with an annular groove in which is mounted a circular spring 71 for urging the balls 69 into one or the other of the depressions 65 and 66.

75 In order to operate the switch member 24

between open and closed circuit positions, the control member 68 is provided with a circular groove 72 into which projects the extension 58 of the switch member 24, the sides of the groove 72 serving as the sole operating connection between the operating lever 64 and the switch member 24. Secured to the reciprocal member 61 is a cam 73 having oppositely inclined faces meeting in a crest 74, and a circular spring 75 is provided for engaging one or the other of the 10 inclined faces of the cam 73 in order to move the reciprocal member 61 with a snap action, the spring 75 being held against movement by a pair of spaced plates 76 and 77 secured to the base 59 by means of a supporting arm 78. 15

When it is desired to energize the device 10 and the contactor 14, the shipper rod 64 is operated in a right-hand direction as viewed in the drawings, to take up the lost motion provided by the connection 63 and operate the link 62, 20 the reciprocal member 61 and the cam 73 carried thereby toward the base 59. Longitudinal operation of the reciprocal member 61 in this direction urges the cam 73 against the spring 75 which engages the plate 77, and the spring 75 is thus 25 forced up the right-hand inclined face of the cam 73 as the cam moves. As soon as the crest 74 of the cam passes through the spring 75, the spring contracts and exerts a force on the left-hand face of the cam 73, whereupon the 30 reciprocal member 61 is operated with a snap action in a right-hand direction, the lost motion connection 63 permitting snap action independently of the control lever 64. As the reciprocal member 61 moves to the right the control member 68 is carried therewith, the spring pressed balls 69 being maintained in the depression 66 to maintain a driving connection, and the left-hand shoulder of the circular groove 72 engages the extension 58 of the switch member 24 to 40 operate the switch member against the force exerted thereon by the segmental gear 21. An energizing circuit is thereby completed for the winding 13 of the contactor 14 and for the energizing winding 18 of the device 10, which circuits 45 have already been traced in connection with Fig. 1.

In order that the switch member 24 may be free, for automatic operation to its open circuit position by the electroresponsive device 10, the 50 manually operable control device is provided with means for automatically freeing the switch member 24 as soon as the contacts 27 are closed. When the bridging member 26 on the switch member 24 engages the contacts 27, continued 55 movement of the control member 68 in a right-hand direction is prevented and the force exerted by the spring 75 is thereupon sufficient to overcome the driving connection established by the balls 69 and the spring 71. Accordingly, the 60 reciprocal member 61 continues to move to the right and the balls 69 are forced by the inclined face of the depression 66 toward the crest 67. As soon as the balls 69 pass over the crest 67, the control member 68 is moved in a left-hand 65 direction with a snap action by the spring 71 to the position shown in Fig. 6, thereby freeing the end 58 of the switch member 24 for operation to the open circuit position at any time.

The switch member 24 may be manually operated to the open circuit position at any time 70 simply by moving the control rod 64 in a left-hand direction, the operation of the control device being exactly the same as when the rod 64 is actuated to close the switch member 24, that 75

is, the spring 75 passes over the crest 74 and engages the right-hand face of the cam 73 to move the reciprocal member 61 to the left with a snap action and when the switch member 24 reaches its extreme open position, the load imposed upon the control member 68 thereby will be sufficient to overcome the driving connection established by the balls 69 and the spring 71, and the balls 69 will move out of the depression 65 and pass over the crest 67 to operate the control member with a snap action to the reset position shown in Fig. 5.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

20 What I claim as new and desire to secure by Letters Patent of the United States, is:—

1. A control device comprising a movable switch member, means including a gear having a portion arranged to engage said switch member 25 for controlling the same, a movable pivot for said gear, electroresponsive means for effecting rotation of said gear about said pivot in response to variations in the energization of said means, time delay means including a toothed element 30 meshable with said gear for retarding the rotation of said gear in a direction to operate said switch member to one position upon a variation in the energization of said electro-responsive means, and means for moving said pivot to disengage said gear from said time delay means and for simultaneously varying the energization of said electro-responsive means to effect movement of said gear, whereby said switch member is operated to said one position substantially instantaneously.

2. A control device comprising a movable switch member, means including a segmental gear for controlling said switch member, a movable pivot for said gear, electro-responsive means 45 for effecting rotation of said segmental gear about said pivot in response to variations in the energization of said means, time delay means including a toothed element meshing with said segmental gear for retarding the rotation of 50 said gear in a direction to operate said switch to one position, whereby said switch member is operated to said one position a predetermined time after a variation in the energization of said electro-responsive means, and means for moving said floating pivot to disengage said segmental gear from said time delay means and for simultaneously varying the energization of said electroresponsive means to effect movement of said segmental gear, whereby said switch member is 55 operated to said one position substantially instantaneously.

3. A control device comprising a switch member normally biased to closed circuit position, means including a segmental gear for operating 65 said switch member to open circuit position, a floating pivot for said gear, electroresponsive means for effecting rotation of said segmental gear about said pivot in response to variations in the energization of said means, time delay means including a toothed element meshing with 70 said segmental gear for retarding the rotation of said gear in a direction to operate said switch member to open circuit position, whereby said switch member is operated to open circuit position with a time delay, and means for moving

said floating pivot to disengage said segmental gear from said time delay means and for simultaneously varying the energization of said electroresponsive means to effect movement of said segmental gear, whereby said switch member is 5 operated to open circuit position substantially instantaneously.

4. A control device comprising a switch member normally biased to closed circuit position, means including a segmental gear for operating 10 said switch member, a movable pivot for said segmental gear, an electromagnet having a movable element connected to said segmental gear, whereby said segmental gear is rotated about said pivot to operate said switch member to open 15 circuit position when said electromagnet is de-energized and to closed circuit position when said electromagnet is energized, time delay means including a toothed element meshing with said segmental gear for retarding the rotation of said 20 gear in a direction to operate said switch member to open circuit position, whereby said switch member is operated to open circuit position a predetermined time after deenergization of said 25 electromagnet, and means for moving said pivot to disengage said segmental gear from said time delay means and for simultaneously deenergizing said electromagnet to effect movement of said segmental gear, whereby said switch member is operated to open circuit position substantially 30 instantaneously.

5. A control device comprising a movable switch member, means including a gear having a portion arranged to engage said switch member 35 for controlling the same, a movable pivot for said gear, electroresponsive means for effecting rotation of said gear about said pivot in response to variations in the energization of said means, time delay means including a toothed element meshable with said gear for retarding the rotation 40 of said gear in a direction to operate said switch member to one position upon a variation in the energization of said electroresponsive means, means for moving said pivot to disengage said gear from said time delay means and for simultaneously varying the energization of said electroresponsive means to effect movement of said gear, whereby said switch member is operated to said one position substantially instantaneously, and means for automatically positioning said 45 toothed element in meshable relation with said gear after instantaneous operation of said switch member.

6. In combination, a time delay mechanism including a rotatable toothed element and a one-way clutch for permitting free operation of said element in one direction, a rotatable gear having a toothless portion normally adjacent said toothed element, a movable pivot for said gear, means for biasing said gear and said pivot to 60 normal position, means for rotating said gear about said pivot whereby said toothed element is driven in said one direction, said time delay mechanism retarding return movement of said gear, means for moving said pivot to disengage 65 said gear from said toothed element whereby said return movement of said gear is unrestrained, and means including said toothless portion of said gear for automatically positioning said toothed element in meshable relation with said 70 gear after said gear has returned to said normal position.

7. In combination, a time delay mechanism including a rotatable driving pinion and a one-way clutch for permitting free operation of said 75

pinion in one direction, a segmental gear having a toothless portion of its periphery normally adjacent said pinion, a movable pivot for said segmental gear, means for rotating said segmental gear about said pivot, whereby said pinion is driven in said one direction, said time delay mechanism retarding return movement of said segmental gear to its normal position, means for moving said pivot to disengage said gear from said pinion whereby return movement of said gear is unrestrained, means for biasing said segmental gear to said normal position, and means including said biasing means for automatically positioning said pinion in meshable relation with said segmental gear after said gear has returned to said normal position.

8. A combined automatic undervoltage and manual control station comprising an electroresponsive device having a movable element, a movable pivot, a segmental gear mounted on said pivot and connected to said movable element for

operation thereby about said pivot, a switch member biased to closed circuit position and arranged to be operated from said position by said segmental gear, manual switch means for momentarily initially energizing said electroresponsive device to operate said segmental gear away from said switch member, whereby said switch member moves to closed circuit position to establish a holding circuit for said electroresponsive device, time delay means including a toothed element meshing with said segmental gear for retarding movement of said gear toward said switch member upon the occurrence of undervoltage conditions, whereby said switch member is operated to open circuit position with a time delay, and manual means for moving said pivot to disengage said segmental gear from said time delay means and for simultaneously opening said holding circuit to said electroresponsive device.
